UNITED STATES PATENT OFFICE.

MAX SCHUCHT, OF MILWAUKEE, WISCONSIN.

CLOCK-ESCAPEMENT.

No. 851,034.

Specification of Letters Patent.

Patented April 23, 1907.

Application filed February 16, 1906. Serial No. 301,344.

To all whom it may concern:

Be it known that I, MAX SCHUCHT, a citizen of the United States, residing at Milwaukee, in the county of Milwaukee and State of Wisconsin, have invented certain new and useful Improvements in Clock-Escapements, of which the following is a specification, reference being had to the accompanying drawings, forming a part thereof.

10 The main objects of this invention are to reduce friction in the escapement, to remove the drag or resistance of a constant connection with the actuating-train from the pendulum, to enable a clock to run for a long time without rewinding, and generally to improve the construction and operation of devices of this class.

15 It consists in certain novel features of construction and in the peculiar arrangement and combinations of parts, as hereinafter particularly described, and pointed out in the claims.

20 In the accompanying drawings like characters designate the same parts in the several figures.

25 Figure 1 is a front elevation, on a greatly-enlarged scale, of a clock-escapement embodying the present invention. Fig. 2 is a side elevation and cross-section on the line 2 2, Fig. 1; and Figs. 3, 4, and 5 are detail views of parts of the mechanism.

30 The pendulum *a* terminates at its lower end in a point or projection *b* and is provided with a delicately-yielding and pivoted pawl *c*, the movement of which relative to the pendulum is limited by a keeper *d*.

35 *e* is the scape-wheel, having teeth constructed and arranged when released to engage one after another with the point or projection *b* of the pendulum and to impart impulses thereto at intervals.

40 *f* is a rotary cylindrical detent provided with an arm *g*, projecting radially therefrom and cut away on one side or formed with a recess *h* to receive and permit the passage one after another of the teeth of the scape-wheel. This detent is constructed and arranged to normally engage with a tooth of the scape-wheel, as shown in Fig. 1, and to 45 hold said wheel quiescent in such position that the point or projection *b* of the pendulum will clear the two uppermost teeth.

45 *i* is a gear-wheel concentric or coaxial with the detent *f* and capable of turning independently thereof. It is provided on one

side with a pin or projection *j*, into whose path the arm *g* of the detent projects.

A toothed wheel *k*, fixed on the arbor of a pinion *l*, meshing with the gear *i*, is arranged in the path of the pawl *c* on the pendulum, 60 and upon the same arbor is fixed an arm *m*, having its outer end laterally extending. The path described by the outer end of this arm intersects the path described by the outer end of the arm *g*. 65

o is a pivoted gravity-dog engaging with the teeth of the pinion *l*, as shown in Fig. 4, and preventing backward rotation of the toothed wheel *k* by the pawl *c*.

70 The escapement operates as follows: At each swing of the pendulum to the right, as shown in Fig. 1, the pawl *c* engages with a tooth of the wheel *k*, turning it an interval corresponding with a single tooth. In the backward swing of the pendulum to the left 75 the pawl *c* swings and yields freely toward the pendulum and rides lightly over the succeeding tooth of the wheel *k* without effect thereon and without appreciable effect on the movement of the pendulum. With each 80 partial turn of the wheel *k* the gear *i* is turned an interval by the pinion *l*, the direction of rotation of the several parts of the escapement being indicated by arrows on Fig. 1. The gear *i* being thus turned step by step, the 85 pin *j* is carried into engagement with the arm *g* and then turns the detent *f* with it and carries the recess *h* toward the tooth of the scape-wheel *e* held by said detent. When the detent is thus brought to releasing position, as shown in Fig. 1, the arm *g* is carried 90 into the path of the arm *m*, which thereupon with the next partial turn of the wheel *k* from the position in which it is shown in the same figure engages and instantly throws the arm *g* forward, turning the detent *f* far enough to release the tooth of the scape-wheel *e* held thereby. This tooth, instantly passing into and out of the recess *h* by engagement with the advance side or edge of said recess, turns 95 the detent *f* into position to catch and stop the next succeeding tooth of the scape-wheel, said recess being carried out of the path of the last-mentioned tooth. The tooth next in advance of the tooth just released immediately following and engaging, as indicated by dotted lines on Fig. 1, with the point or projection *b* of the pendulum as it 100 swings to the right imparts an impulse thereto. These operations being repeated, as 105

110

- above explained, impulses are imparted to the pendulum at sufficiently frequent intervals to keep it in vibration, while during the intervals between the impulses the pendulum swings freely without obstruction or impediment to its movement, being disconnected and free from the actuating-train. The laterally-extended end of the arm *m*, standing after the release of each tooth of the 5
 10 scape-wheel by the detent *f* in the path of the arm *g*, as shown in Fig. 5, prevents the overthrow of the detent by the advance of the released tooth of the scape-wheel into position to clear and permit the passage of the succeeding tooth until the gear-wheel *i* has made another complete revolution and its pin *j* by engagement with the arm *g* has turned the detent *f* again to releasing position in the manner above explained.
 15
 20 As shown in the drawings, the wheel *k* and the pinion *l* each have eight teeth, the gear *i* has forty-eight teeth, and the scape-wheel *e* has ten teeth, so that the gear *i* makes one complete revolution and releases the scape-wheel once to every six revolutions of the wheel *k* and every ninety-six vibrations of the pendulum, and the scape-wheel makes one complete revolution to every ten revolutions of the gear *i*; but the number of teeth 25
 30 which the several wheels have may be varied without affecting the essential mode of operation and principle of the escapement.

By the application of an escapement of this kind to a clock having a movement like 35 or similar to those of thirty-day clocks now in use it may be made to run a year without rewinding.

Various changes in the details of construction and arrangement of parts, particularly 40 in the mechanism for communicating movement from the pendulum to the detent which holds and releases the scape-wheel, may be made without departing from the principle and intended scope of the invention.

45 I claim—

1. In a clock the combination with the pendulum, of a scape-wheel having teeth constructed and arranged to engage one after another with the pendulum and to impart 50 impulses thereto when said wheel is released, a stop adapted to normally hold said wheel against turning, and stop-actuating mechanism operated by the pendulum and adapted to intermittently release said wheel at intervals, each including several oscillations of the pendulum in each direction, substantially as described.

2. In a clock-escapement the combination with the pendulum, of a scape-wheel the 55 teeth of which are constructed and arranged to engage with and impart impulses to the pendulum; a rotary detent normally engaging a tooth of the scape-wheel and holding

said wheel in such position that its teeth will be cleared by the pendulum, a wheel provided with a projection arranged to engage with said detent and to turn it to releasing position, and mechanism operated by the pendulum to turn said detent-actuating wheel, substantially as described. 65

3. In a clock-escapement the combination with the pendulum, of a scape-wheel having teeth constructed and arranged to engage one after another with the pendulum and to impart impulses thereto at intervals, a rotary cylindrical detent arranged to normally engage with a tooth of the scape-wheel and hold it clear of the pendulum, and recessed on one side to receive and permit the passage of such tooth, and a wheel actuated by the pendulum and adapted to turn said detent, substantially as described. 70 75

4. In a clock-escapement, the combination with the pendulum provided with a pawl, of a scape-wheel adapted when released to engage with and impart impulses to the pendulum, a rotary detent adapted to normally engage with a tooth of said wheel and provided with an arm, a wheel having a projection arranged to engage with the arm of said detent 85 and turn it to releasing position, and a toothed wheel actuated by the pawl on the pendulum, geared with said detent-turning wheel and provided with an arm arranged to quickly turn the detent forward into releasing position when its arm is engaged by the other arm, substantially as described. 90 95

5. In a clock-escapement the combination with the pendulum provided with a pawl, of a scape-wheel having teeth normally clearing the pendulum and adapted when released to engage therewith one after another and to impart impulses thereto, a rotary detent normally engaging with a tooth of said wheel and provided with an arm and with a recess 100 for clearing and releasing such tooth, a gear-wheel having a projection arranged to engage with the arm of said detent and to turn the detent to releasing position at each revolution of the gear-wheel, a toothed wheel actuated by the pawl on the pendulum and provided with an arm arranged to quickly turn the detent forward into releasing position when its arm is engaged by the other arm which is extended at the end and serves as a 105 stop to prevent overthrow of the detent after each release of the scape-wheel, and a pinion mounted on the toothed wheel-arbor and meshing with said gear-wheel, substantially as described. 110 115 120

In witness whereof I hereto affix my signature in presence of two witnesses.

MAX SCHUCHT.
